UNITED STATES PATENT OFFICE.

ALBERT J. ELKINS, OF CORAL, MICHIGAN.

MARL-DIGGING MACHINE.

Application filed July 26, 1926. Serial No. 125,049.

This invention relates to a marl digging machine. Marl is ordinarily found at the bottom of small lakes or ponds and in many instances is in very soft condition. It is an object and purpose of the present invention to provide a means for digging and removing the marl in a quick and expeditious manner, and provide a digging device which is capable of removing the marl irrespective of its condition as to hardness, the device which I have invented being particularly capable in connection with marl in its softer state, in many instances of which it is of almost if not quite liquid consistency.

A further object of the invention is to provide a digging device of the character stated, which may be drawn to a desired place over the marl bed, and may then be drawn in the reverse direction, the machine working automatically to remove a portion of the marl, the depth removed being governed by a certain adjustment of the machine, and when the machine has been drawn from the bed and elevated to a certain height to automatically trip the same to dump the marl which has been removed, so that the digging machine may be empty for its succeeding load. On its return, it is automatically latched and a device which adjusts and governs the depth that the digging apparatus shall enter into the marl bed is turned automatically to operative position so that with the machine, it is merely necessary to pull it in one direction to a desired position on the marl bed and then draw it in the opposite direction until it is automatically tripped and dumped, whereupon the cycle of operation may be repeated for a succeeding load.

For an understanding of the invention and the construction which I have made to embody the same, reference may be had to the following description taken in connection with the accompanying drawings, in

which

Fig. 1 is an elevation showing the marl digging apparatus installed for operation and with the digging device in position and indicated as moving in a direction to remove a load from the marl bed.

Fig. 2 is a fragmentary elevation similar to that shown in Fig. 1, illustrating the position of the digging device as it is being drawn backward over the marl bed.

Fig. 3 is an elevation showing the way that the digging scoop is dumped.

Fig. 4 is an enlarged longitudinal vertical section through the digging apparatus which forms the main essential part of my invention.

Fig. 5 is a plan view thereof, and

Fig. 6 is a transverse vertical section through the apparatus shown in Figs. 4 and 5, the section being taken in front of the latching device and looking to the rear.

Like reference characters refer to like parts in different figures of the drawings.

In the construction of the digging device itself, an upper frame is made having spaced apart sides 1, preferably formed of flat bars of metal, the same being connected at their rear ends by an inverted U-shaped stirrup which has an upper horizontal side 2 and depending legs 3. A pivot bolt 4 extends through the lower end of each leg 3 and through the vertical sides 5 of a digging scoop which is of sheet metal and is completed by a bottom 6 and a rear vertical end 7, the front end being open. The pivot bolts 4 pass through the sides 5 near their upper rear corners as best shown in Fig. 4. Across the front end of the digging scoop, a flat bar 8 is passed having depending legs 9 which lie alongside of the sides 5 of the scoop and are permanently secured thereto by rivets. A rod 10 extends upwardly from the bottom of the scoop and through the bar 8, receiving a nut at its upper end, this being for the purpose of strengthening and reinforcing the bottom of the scoop at its open front end when the same is loaded and held by a latch in loaded condition as will hereafter appear. At the upper side of bar 2, two spaced apart flat vertical posts 10 are permanently secured substantially midway between the ends of said bar 2 between which, near their upper ends, a pulley 11 is rotatably mounted. Below the pulley a plate 12 of metal is located and permanently secured to one of the posts 11 and to which one of the cables used to move the apparatus back and forth is to be attached.

The front ends of the side bars 1 are connected by a front cross bar 13 from which, at its upper side and near its middle, two vertical posts 14 of flat bar metal project between which a pulley 15 is held and rotatably mounted, said pulley being in substan-

tially the same horizontal plane with the pulley 11 previously described. In addition, below the pulley 15, a plate 16 is permanently secured to the posts 14 to which the other 5 of the cables for moving the device back and forth is to be secured.

A horizontal flat bar 17 lies between one of the posts 10 and one of the posts 14, and is secured at the ends to these posts. A latch 10 bar 18 is pivotally mounted between its ends, at 19, on the bar 17 and at its lower end formed with a latching hook 20 to engage with the cross bar 8 above and at the front end of the digging scoop, being normally 15 moved into engaging position by a tension spring 21 disposed between the upper end of latch bar 18 and the bar 17 on which it is mounted. This spring tends to turn the latch bar in a clockwise direction until 20 stopped by a stop 22 shown in Fig. 4 as permanently attached to bar 17. A link 23 is pivotally connected at its rear end to the upper end of the latch bar 18 and extends horizontally forward between the vertical 25 posts 14, and at its front end is equipped with a depending U-shaped stirrup 24 between the sides of which a pulley 25 is mounted, said pulley 25 lying in horizontal alignment with the pulleys 11 and 15 which 30 were earlier described.

At a point a distance in front of the open end of the digging scoop, two flat bars 26 are located one adjacent each of the sides 1 of the frame, each of which is formed with a plurality of openings 27 through it, through 35 which pivot pins or bolts 28 may pass so as to adjustably pivot the bars 26 on the frame bars 1. Between the lower end portions of the bars 28, a cross board or plate 29 is 40 located and secured. Two chains 30 are connected at their lower ends, respectively, to the lower ends of the bars 26 and at their upper ends to the frame bars 1. The bars 26 are formed of two sections lying at an 45 angle to each other and the openings and holes 27 through them pass around the angle made by said two sections. It is evident that the cross board 29 may be adjusted to several positions with respect to the front open 50 end of the digging scoop, and when the chains 30 are straightened out, as shown in dotted lines in Fig. 4, such cross board will serve to guide the front end of the scoop over the marl bed and permit it to dig thereinto 55 only a prescribed and limited distance. In fact whatever the consistency the marl may be, no matter how soft, the digging scoop cannot sink and submerge itself therein, as its front edge is held against digging into the bed any farther than it is permitted to enter by the cross board 29 which rides over the upper surface of the bed.

The digging device which has been described is installed in connection with the 60 bed which is to be dug, two vertical posts

31 and 32 being fixed at their lower ends in the earth at each side of the bend, the former of which is considerably higher than the latter. A cable 33 is attached to the plate 12 and extends to and around a pulley 34 carried at the upper end of the shorter post 32 and thence extends substantially horizontally forward to and beyond the post 31. It is clear that on drawing on the cable 33 by any suitable source of power, the digging apparatus and its scoop may be drawn towards the post 32. This movement is illustrated in Fig. 2 in which case the digging scoop will ride over the bed and the device pivotally mounted at the front end of the digging 75 scoop consisting of the bars 26 and the cross bars 29, will be automatically moved in a counter clockwise direction away from the open front end of the scoop.

A second cable 35 is fixed at one end to the plate 16 and extends upwardly and forwardly over a pulley 36 mounted near the upper end of the higher post 31, cable 35 extending therefrom downwardly and forwardly. A pull on this cable moves the digging scoop and the frame on which it is mounted in the direction indicated in Fig. 1, whereupon the open end of the scoop tends to enter the bed and fill it with the material thereof but is held from entering too far and submerging 90 itself by reason of the depth gauge apparatus previously described comprising the bars 26, cross board 29 and the chains 30. As soon as the digging apparatus starts to move in the direction of the arrow indicated in Fig. 1, this depth gauge member swings from the position shown in Fig. 2 or as far as the chains 30 will permit it to go, and thus automatically gauges the depth that the digging scoop may enter into the bed. 95

The digging apparatus is mounted on a trolley cable 37 which passes underneath the pulleys 11, 15, and 25. The trolley cable is secured at one end to the post 32 and at its other end portion passes over a pulley 38 located above a pulley 36 on the post 31, and is then carried downwardly to and snubbed around an anchor post 39. The trolley cable 37, as is evident, may be slackened or tightened to a greater or less degree 110 so as to change the position at which the scoop engages the bed from which it is to remove material.

On the trolley cable 37 a trip block 40 is adjustably secured, being shown in Fig. 1 120 as located a short distance from the pulley 38. When, as shown in Fig. 1, the digging apparatus has been drawn backwardly to a desired position, and is then moved in a forward direction so as to fill or partially 125 fill the scoop, on its continued forward movement the digging apparatus moves upwardly on the trolley cable 37, elevating the scoop and the load which it carries until such time as the stirrup 24 comes against the trip 130

block 40. When this occurs the link 23 is moved rearwardly with respect to the frame turning the latch bar 18 and disengaging the latch 20 from the cross bar 8. When this 5 occurs the front open end of the scoop is free from the latch and it turns by gravity to the position shown in Fig. 3, thereby automatically dumping the load which the scoop has gathered. Then by slackening off on the 10 cable 35 and drawing on the cable 33 the digging apparatus may be returned to its lower position; and as soon as the scoop strikes against the ground or anything else with sufficient resistance it is automatically 15 turned about the pivot bolts 4 and connected with the latch 20 which is free to return to latching position as soon as the stirrup 24 moves away from the trip block 40.

This apparatus is very practical and efficient and has proved its utility in extensive practical use. While I have referred specifically to the digging of marl as being one place where the invention is of great use, it is to be understood that the apparatus is 25 available for digging and carrying or for carrying alone a great variety of materials other than marl, being especially useful for reaching places which are inaccessible for trucks, wagons, or other vehicles in which 30 material is carried. My invention accordingly is not to be limited to use in the one place specifically described.

The invention is defined in the appended claims and is to be considered comprehensive 35 of all forms of structures coming within their scope.

I claim:

1. Digging apparatus of the character described comprising, a horizontal supporting 40 frame, means for suspending and mounting said frame for movement back and forth on a trolley, a digging scoop located below the frame at the rear portion thereof and pivotally mounted at its rear upper corners on 45 the frame, a vertically disposed latch bar pivotally mounted on said frame adjacent the front open end of the scoop with which the latch bar engages at its lower end to hold the scoop in a horizontal position, 50 spring means acting on the latch bar to normally engage said bar with the scoop, a link connected to the upper end of the latch bar and extending horizontally in a forward direction, means at the front end of the link 55 adapted to traverse said trolley whereby when the apparatus is moved along said trolley to a predetermined point said means may engage a trip secured on said trolley to thereby unlatch the scoop.

60 2. A construction containing the elements in combination defined in claim 1, combined with bars pivotally mounted on the frame at the front of the scoop, a cross board connecting the lower ends of said bars, and a 65 chain connected at one end of the frame and

at the opposite end to the lower end of one of said bars whereby in its rearward position the lower edge of said cross board lies a short distance above the lower end of the scoop.

70 3. A construction containing the elements in combination defined in claim 1, combined with two bars pivoted one to each side of the frame, a distance in front of the scoop, each of said bars having a plurality of openings in the length thereby whereby the same may be pivoted at different points on said frame, a cross board connecting the lower ends of the bars, and flexible means connected to the frame and to said bars for limiting the rearward position of said cross board.

75 4. In a construction of the class described, two spaced apart frame bars, an inverted U-shaped member disposed between and connected to the rear ends of said frame bars, a digging scoop having vertical sides, a horizontal bottom and a vertical rear end located between the depending legs of said U-shaped member, pivot bolts passing 80 through said legs and the sides of scoop adjacent the rear upper corners of said sides, a bar located transversely above and secured to the scoop at its front open end, a cross bar disposed between and connecting the 85 front ends of the frame side bars, a pair of vertical posts connecting to and extending upwardly from said cross bar, a second pair of posts extending upwardly from said U-shaped member, pulleys under which a trolley cable may pass mounted between each 90 of said pairs of posts, a horizontal bar located between and connected to one post of each of said pairs, a vertical latch bar pivotally mounted between its ends on said horizontal bar and formed at its lower end with a hook to engage with the transverse bar at the front end of the scoop, a coiled tension spring connected at one end to the horizontal bar and at its opposite end to the latch bar above its pivot, a link pivotally connected at its rear end to the upper end of the latch bar and extending horizontally 95 forward between the front pair of vertical posts, a stirrup depending from the front of said link, a pulley mounted between the sides of the stirrup under which the trolley may pass, and means whereby cables may be secured one at each end of the frame.

100 5. A construction containing the elements in combination defined in claim 4, combined with two bars one pivotally connected to each of the side bars of the frame and having lower depending portions, a cross board disposed between and connected to said depending portions, and two chains connected at one end to the side bars of the frame and at their opposite ends to the lower ends of the depending portions of the last mentioned 105 bars.

6. In combination, spaced apart posts one higher than the other, a trolley cable fastened at one end to the lower post, a pulley attached to the upper end of the higher post 5 over which the trolley cable passes, an anchor post around which the end of the trolley cable is adjustably fastened, a digging device including a frame and a digging scoop pivotally mounted at one end on said frame, 10 said digging device being mounted on said trolley cable, means for moving the digging device in opposite directions on said trolley cable, latching means on said digging device automatically connecting with the scoop 15 to hold it parallel to the frame on movement of said digging device toward the shorter post, a trip block on the trolley cable near said higher post, means connected with the latching means adapted to engage said 20 trip block and move the latching means from engagement with the scoop for dumping its contents when the digging device is moved towards said higher post, a depth gauge piv-

otally mounted on the same in front of the front end of the scoop, said depth gauge 25 moving towards the front end of the scoop when the digging device is drawn towards the higher post, said depth gauge extending transversely across the front end of the scoop so as to ride on the upper surface of the material to be dug, and means for limiting the movement of said depth gauge towards the front end of the scoop. 30

7. Digging apparatus of the character described comprising a trolley, a digging scoop having an open forward end and pivotally suspended on the trolley at its rear end, detachable means for suspending the front end of the scoop from the trolley and a depth gauge mounted on said trolley and comprising a bar extending across and in front of the open end of the scoop above the bottom thereof. 35

In testimony whereof I affix my signature.

ALBERT J. ELKINS.
